UNITED STATES PATENT OFFICE.

JOHN S. MALLARY AND JAMES A. LEONARD, OF YOUNGSTOWN, OHIO.

INK-WELL.

SPECIFICATION forming part of Letters Patent No. 554,785, dated February 18, 1896.

Application filed January 4, 1896. Serial No. 574,332. (No model.)

To all whom it may concern:

Be it known that we, JOHN S. MALLARY and JAMES A. LEONARD, citizens of the United States, residing at Youngstown, in the county 5 of Mahoning and State of Ohio, have invented certain new and useful Improvements in Ink-Well; and we do hereby declare the following to be a full, clear, and exact description of our invention, such as will enable others 10 skilled in the art to which it appertains to make and use the same, reference being had to the accompanying drawings, which form part of this specification.

The object of our invention is an ink-well, 15 designed especially for use in school-desks, that combines the following qualities not heretofore found combined in ink-wells and of great importance in such use, namely: First, there is an absence of rattle, noise, or movement under the ordinary circumstances of use; second, the perfect plane of the desk-surface without projection or indentation is substantially preserved; third, the well is conveniently removed from and put into place, 20 and having a removable top may be quickly and perfectly cleaned and refilled; fourth, when not in use the ink is sealed against impurities and evaporation; fifth, in opening for use the little force necessary effects that 25 result without attention, the same being true of the closing after use, and, sixth, nothing is presented with which the pupil is induced to toy, and no opportunity for breakage or damage to the well or of ink soil or stain to the 30 pupil is presented. All teachers in schools where writing is taught or used will appreciate the great value of an ink-well presenting the qualities enumerated. We accomplish this object by the device hereinafter 35 described and illustrated in the drawings, in which—

Figure 1 is a top view of a section of a school-desk provided with our ink-well. Fig. 2 is a vertical sectional view of the same on the line $y y$ of Fig. 1. Fig. 3 is a side elevational view of our bottle B. Fig. 4 is a view of the under side of the bottle-cover C, and Fig. 5 is a similar view of the revolving opening and closing disk D.

50 The parts are indicated by letters, and similar letters refer to similar parts in all views.

The bottle B, preferably a blown-glass bot-

tle, is round, entirely open at the top, a little below which top there appears around its periphery a collar having oppositely two short 55 downwardly-tapering lugs, each integral with the bottle and exterior to it, said collar and lugs being for the purpose of holding the bottle in place in the opening in the desk-top that receives it, such opening being fashioned 60 with a shoulder for said collar and vertical recesses for said lugs, so that in place the bottle snugly fits therein. Preferably we make the bottle B of a depth to correspond with the thickness of the desk-top so that the 65 lower end of the bottle does not protrude, increasing the diameter for suitable capacity.

The exterior of the bottle above the collar is threaded for a means of attaching the cover C. The cover C is a disk, from the edge 70 gradually thickening to the center to give better hold for the central pivot-pin p, having a slightly-upward and a larger downward annular rim, the downward portion being threaded to engage with the threads on the 75 bottle B in attaching the cover C, the upward portion being to form the side of the cup in which the revolving disk D has place, the edge on a plane with the upper surface of the disk D. The round opening o' through the 80 cover C is of suitable size to give pen access to the interior of the bottle and is located near the periphery. The cheek c is an integral projection appearing on the inner side of the downward portion of the rim at the 85 proper point for the purpose that will presently appear.

The revolving disk D is of size to snugly but movably fill the cup presented on the upper side of the cover C in which it rests. It has 90 a central opening for the pivot-pin p, the flat head of which is countersunk therein, and the round opening o for the passage of the pen near the periphery exactly corresponding in location and size to the opening o' in the 95 cover C, on each side of which round opening are formed indented nail-catches similar to those seen upon the blades of pocket-knives. On the under side at its periphery appears the inwardly-cut slot or rabbet, occupying a 100 segment in length something more than double the diameter of the pen-opening o, which is exactly opposite its central line. This under side, to render the bottle B as nearly air-

tight and impenetrable by dust as possible, we coat with a layer of rubber, corkwood, or other soft material o^2 , preferably rubber, attaching the layer by any suitable cement.

5 To still further protect the ink from evaporation and accumulation of impurities we place, in assembling the parts, on the upper edge of the collar of the bottle the packing p' , preferably of rubber, similar to that used 10 in fruit-cans.

The pivot p , which extends downward through the revolving disk D, its head countersunk therein, as explained, passes through the central aperture of the cover C, the portion 15 protruding below being threaded, so that by the use of a small nut it may be held, holding the cover C and the revolving disk D together, the latter easily rotatable.

For the cover C and the revolving disk D 20 we preferably use a non-corrosive metal, zinc being preferable, both being cut by suitable dies.

Our invention will now be understood and 25 its usefulness in accomplishing the object stated in the beginning of this specification will be appreciated.

We are well aware that inkstands capped 30 with revolving disk covers having openings to be brought into coincidence with openings 35 in the bottle-neck for access to the ink have been made, but we are not aware that an ink-well especially adapted to school use, constructed of the combination of parts above described and producing the results stated as our object, was ever known until our invention thereof.

What we claim is—

In an ink-well the combination of the open-

topped neckless bottle B having an integral annular collar a little below the top and two 40 integral downward-tapering lugs, said bottle being adapted to enter an opening in a desktop that has a shoulder and recesses to fittingly receive it; the disk-shaped bottle-cover C, thickest at the center having a central aperture, and having around its periphery a rim projecting above and below the disk, the lower portion being largest and interiorly threaded, and having near its rim the pen-opening o' , the cheek c upon the inner side of 45 the upper portion of said rim; the soft packing p' between the lower edges of the rim of the cover C and the collar upon the bottle B; the revolving disk cover D, suitable to fill the cup located on the upper surface of the cover 50 C, having a central opening and near the periphery the pen-opening o , indented nail-catches, on each side of the cover, said cover having upon its under side, which is lined with rubber or other soft material, at the periphery, the segmental slot or rabbet s occupying a space something more than twice the diameter of the pen-opening o ; and the pivot-pin p , its flat head countersunk in the revolving disk D, threaded at its lower extremity 55 for engagement with a nut below the cover C; all substantially as described and for the purpose expressed.

In testimony whereof we hereunto affix our signatures in the presence of two witnesses. 60 70

JOHN S. MALLARY.
JAMES A. LEONARD.
